UNITED STATES PATENT OFFICE.

WILLIAM WELSHAUSEN, OF ALLENHURST, NEW JERSEY.

LIQUID-FUEL BURNER.

1,250,060.

Specification of Letters Patent. Patented Dec. 11, 1917.

Application filed April 11, 1917. Serial No. 161,248.

To all whom it may concern:

Be it known that I, WILLIAM WELSHAUSEN, a citizen of the United States, residing at Allenhurst, in the county of Monmouth and State of New Jersey, have invented certain new and useful Improvements in Liquid-Fuel Burners, of which the following is a specification.

This invention relates to liquid fuel burners and while the burner embodying the present invention is designed primarily for use in conjunction with an automobile radiator heating system, the principles of the invention may find embodiment in burners designed for other uses.

It is one object of the invention to provide a liquid fuel burner which may be lighted and left unattended with safety so as to supply heat to the radiator for any desired length of time to prevent freezing of the water therein and, incidentally, to provide highly efficient means for automatically feeding liquid fuel to the burner font as the fuel is consumed.

Another aim of the invention is to provide a burner of the class above mentioned which may be readily and quickly taken down so as to permit of convenient trimming of the wick, and cleaning of the burner parts and their repair if necessary. Incidentally, the invention aims to so construct the burner that the burner proper may be dismounted or taken down without in any way disturbing the means provided for automatically supplying fuel to the burner so that the said means will not be likely to become disarranged and fail to properly perform its function when the burner proper is again mounted in position upon the radiator.

In the accompanying drawings:

Figure 1 is a vertical transverse sectional view through the burner embodying the present invention, the view also illustrating a portion of the heating system for the radiator;

Fig. 2 is a horizontal sectional view on the line 2—2 of Fig. 1 looking in the direction of the arrow;

Fig. 3 is a bottom plan view of the attaching member for the burner proper;

Fig. 4 is a side elevation of the said attaching member.

As before stated, the burner embodying the present invention is designed primarily for use in a radiator heating system and

such a system is disclosed in my co-pending application filed April 11, 1917, Serial No. 161,247, and in the drawings there is illustrated so much of the lower portion of such a radiator as is necessary to illustrate the application of the burner, the numeral 1 indicating in general the base of the radiator and the numeral 2 indicating a flue through which the heated air currents from the burner ascend, the said flue extending upwardly within the radiator and having its lower end extending a short distance below the base 1 of the radiator and exteriorly threaded, as indicated by the numeral 3. The attaching member for the burner proper comprises a body 4 which is formed at one end with an opening 5, the wall of which is threaded to fit the threads 3 upon the projecting lower end of the flue 2, the upper face of the body 4 being plane to seat snugly against the underside of the radiator base 1 it being understood that the attaching body 4 is in this manner firmly supported beneath the radiator. For a purpose to be presently explained the underside of the body 4 is formed with an annular seat 6 surrounding the opening 5. In its said under side the body 4 beyond the opening 5 therein is recessed as at 22 to house the elements of the means provided for automatically controlling the supply of liquid fuel to the burner as will be presently described.

The burner proper includes a burner head 7, the periphery of which is designed to fit snugly within the seat 6 and this head has a number of perforations 8 through which air may enter to sustain the burner flame, the upper portion of the head being housed within the lower end of the flue. The burner further includes a wick tube 19 surrounding which is the usual wick 10 and this wick tube carries the usual flame spreader 11. The tube 9 is open at its lower end and extends axially within the burner font which is indicated by the numeral 12 and which is of suitable capacity and integrally connected by a web portion 13, with a float chamber 14, the web being provided with a passageway 15 establishing communication between the float chamber and the font. The numeral 16 indicates in general the wick raising and lowering device which is of the ordinary construction. The float chamber 14 is open at its upper side and communicates with the recess heretofore re-

ferred to as being formed in the underside of the attaching body 4. To prevent buckling, the bottom of the float chamber 14 is downwardly bulged, as at 17. The means 5 provided for connecting the burner as a whole with the attaching member 4 is in the nature of a yoke including side members 18 and a lower connecting member 19, the yoke being disposed to straddle the attaching body 4 and the float chamber 14 and the 10 upper ends of the side members of the yoke being pivoted, as at 20, to the front and rear sides of the said body 4. Thus the yoke may be swung to the position shown 15 in Fig. 1 of the drawings, in which position its connecting portion 19 will extend beneath the bottom 17 of the float chamber or the yoke may be swung outwardly to the position shown in Fig. 3 of the drawings. A 20 binding screw 21 is threaded through the connecting member 19 of the yoke and may be adjusted, when the yoke is in the full line position shown in Fig. 1 of the drawings, to bear firmly at its upper end against 25 the downwardly bulged bottom 17 of the float chamber so as to cause the upper end of the float chamber to seat against the underside of the attaching body 4, and the burner 7 to seat firmly within the seat 6 30 in the said underside of the body. It will now be understood that when it is desired to remove the burner including the burner head, font 12, and float chamber 14, this may be readily accomplished by loosening 35 the binding screw 21 and swinging the yoke to the left in Fig. 1 of the drawings, whereupon the parts mentioned may be bodily dropped from the attaching member 4. Of course, by reversing this procedure the said 40 parts may be quickly reassembled with the attaching member.

The recess heretofore referred to as formed in the underside of the body 4 is indicated by the numeral 22 and threaded 45 into one end of the body is a nipple 23 for the connection of a fuel conduit (not shown) leading from any suitable source of supply upon the machine, the nipple communicating with a passage 24 formed in the body 4 50 and the said passage at its inner end opening into the recess 22 so that the liquid fuel supplied through the said conduit will pass through the passage 24 and into the float chamber 14. Secured upon the upper wall 55 of the recess 22 beneath the inner end of the passage 24 is a guide 25 in which is vertically slidably mounted the stem 26 of a valve having a conical head 27 designed when moved upwardly to close the inner end 60 of the passage 24 and cut-off the supply of liquid fuel to the float chamber through this passage. Pivottally mounted, as at 28, upon the said upper wall of the recess 22 is an arm 29 which extends beneath the valve 27 65 and upon which the lower end of the valve

stem 26 rests, as clearly shown in Fig. 1 of the drawings. This arm also extends through a depending yoke 30 located within the recess 22 which yoke limits the downward movement of the arm and, consequently, the opening movement of the arm 29. Removably disposed within the float chamber 14 and freely vertically movable therein is a float 31 which, when it rises with the level of the liquid fuel within the said chamber, engages at its upper end with the free end of the arm 29 which end of the arm is preferably curved to form the annular head 32.

From the foregoing description of the invention it will be understood that as the liquid fuel is consumed by the burner the level of the fuel within the float chamber 14 will lower as will also the float 31 and, consequently, the arm 29 will fall allowing the valve 27 to move downwardly to open position. Liquid fuel will then flow through the passage 24 into the float chamber until the float 31 has again moved upwardly into engagement with the free end of the arm 29 and the arm has moved the valve to closed position. Thus the supply of liquid fuel to the burner is entirely automatic and the burner may be lighted and allowed to stand unattended for any length of time without likelihood of too much or insufficient fuel being fed thereto. An overflow pipe 33 leads from the font 12 near the upper end thereof and is of larger diameter than the passage 24 so that should the float 31 fail to operate, the liquid fuel will overflow from the said font, thereby indicating to the user of the burner that the float and parts actuated thereby require attention or adjustment.

Having thus described the invention, what is claimed as new is:

1. In a device of the class described, an attaching member having means for attachment to a flue, a burner detachably assembled with the said attaching member and including a burner proper, a font, a float chamber communicating with the font, a float within the said chamber, the said attaching member having a liquid fuel conductor communicating with the float chamber when the burner is assembled with the said attaching member, and means carried by the attaching member for controlling the flow of liquid from said passage and including an element with which the float is designed to coact.

2. In a device of the class described, an attaching member, a burner detachably assembled therewith and including a float chamber from which liquid fuel is fed to the burner, a float in said chamber, the attaching member having a liquid fuel passage communicating with the float chamber whereby to supply liquid fuel thereto, a

valve for controlling the flow of liquid fuel from said passage, and means carried by the attaching member for controlling the movement of the valve and including an actuating element in the path of the float.

3. In a device of the class described, an attaching member, a burner assembled therewith, a clamp member connected for swinging movement with the attaching member and having means for engagement with the burner whereby to connect the burner with the attaching member, the said burner including a float chamber and the attaching member having means for discharging liquid fuel into the float chamber, a float in said chamber, and means actuated by the float and carried by the attaching member for controlling the discharge of liquid fuel into the said chamber.

20 4. In a device of the class described, an attaching member adaptable to the lower end of a flue, a member removably assembled with the first-mentioned member, a font supported by the second-mentioned member, a burner supported by the font in position to enter the flue when the said members are assembled, a float chamber supported by the second-mentioned member and in communication with the font, a float within the chamber, the first-mentioned member having a liquid fuel passage arranged to discharge into the float chamber, a valve for controlling said discharge, the first-mentioned member having a recessed to house the said valve, means arranged within the recess and actuated by the float to control the movement of the valve, and means for holding the second-mentioned member assembled with the first-mentioned member.

ber being recessed to house the said valve, means arranged within the recess and actuated by the float to control the movement of the valve, and means for holding the second-mentioned member assembled with the first-mentioned member.

5. In a device of the class described, an attaching member adaptable to the lower end of a flue, a member removably assembled with the first-mentioned member, a font supported by the second-mentioned member, a burner supported by the font in position to enter the flue when the said members are assembled, a float chamber supported by the second-mentioned member and in communication with the font, a float within the chamber, the first-mentioned member having a liquid fuel passage arranged to discharge into the float chamber, a valve for controlling said discharge, the first-mentioned member being recessed to house the said valve, means arranged within the recess and actuated by the float to control the movement of the valve, a yoke pivotally connected with the first-mentioned member and adapted to be swung to straddle the second-mentioned member, and a securing screw adjustably threaded through the connecting portion of the yoke to engage the under side of the second-mentioned member.

In testimony whereof I affix my signature. 65
WILLIAM WEISHAUSEN. [L. S.]
